Specification for Design.

Patented Mar. 21, 1922.

Application filed November 19, 1920. Serial No. 425,277. Term of patent 7 years.

To all whom it may concern:

Be it known that I, VONNIE WILSON Woods, a citizen of the United States, residing at Portland, county of Multnomah and State of Oregon, have invented a new, original, and ornamental Design for a Souvenir Wall Hanging or Plaque, of which the following is a specification, reference being had to the accompanying drawing, forming part thereof.

In said drawings,

Fig. 1 shows a front elevation of a souvenir wall hanging or plaque embodying my design; and

Fig. 2 shows a side elevation thereof.

The essential feature of my design is the representation of a full face view of the head of an Indian maiden with her hair loosely streaming down on the sides, and associated with said head is a background suggestive of a teepee.

I claim:

The ornamental design for a souvenir wall hanging or plaque as shown.
